UNITED STATES PATENT OFFICE.

RICHARD D. ANANSON, OF STIRLING, NEW JERSEY.

ATTACHMENT FOR TYPE-WRITING MACHINES.

1,170,385.

Specification of Letters Patent.

Patented Feb. 1, 1916.

Application filed May 17, 1915. Serial No. 28,523.

To all whom it may concern:

Be it known that I, RICHARD D. ANANSON, a citizen of the United States of America, and a resident of Stirling, county of Morris, and State of New Jersey, have invented 5 certain new and useful Improvements in Attachments for Type-Writing Machines, of which the following is a specification, reference being had to the accompanying drawings, forming a part thereof.

My invention relates to typewriting machines and has special reference to manifolding and paper cutting attachments therefor.

One object of my invention is to provide 15 a simple and durable attachment of the aforesaid character that shall be inexpensive to construct and that shall be adapted to be attached readily to well known commercial typewriting machines.

Another object is to provide simple and improved means for cutting the folds of a longitudinally folded strip of paper or fabric as it is being fed into a typewriting machine, whereby a plurality of independent 25 superposed strips are produced.

Another object is to provide means for 30 suitably supporting a plurality of superposed typewriter ribbon strips, and means for guiding sheets or strips of paper between the ribbon strips whereby a plurality of ribbon copies are simultaneously produced.

Still another object of my invention is to provide in an attachment of the character set forth, combined guide and cutting means 35 for permitting the ready removal of any desired length of paper from a typewriting machine which is supplied with a practically continuous strip or strips of paper.

Another object is to provide a simple 40 typewriter attachment which may be quickly and easily mounted on a typewriter machine of usual construction and which shall particularly adapt the machine for making out railroad or steamship freight bills, or 45 the like, together with two or more extra ribbon copies of the same, the bills or the like being made up on printed forms repeated at close intervals on a continuous roll or strip of paper which is folded longitudinally a sufficient number of times to provide 50 an original and such copies as are required, the attachment being adapted to guide the strip onto the typewriter machine, to cut the folded strip along the line of the 55 folds to separate between the copies, to suitably manifold the copies without the use

of carbon paper or the like, and to enable each separate bill when completed, together with the copies, to be quickly removed from the machine and from the remainder of the 60 roll or strip.

Referring to the drawings, Figure 1 is a sectional elevation of an attachment arranged and constructed in accordance with my invention, the coöperating parts of a 65 typewriting machine being also illustrated. Fig. 2 is a view corresponding to Fig. 1, showing the attachment separate from the machine. A perspective view of a manifolding ribbon which is adapted for use 70 with the attachment is shown in Fig. 3. Fig. 4 is a plan view of the attachment and Fig. 5 is a sectional view taken on the line 5—5 of Fig. 1, the adjacent parts of the typewriter machine being shown in broken 75 lines in these figures. Figs. 6 and 7 are sectional detail views taken respectively on the lines 6—6 and 7—7 of Fig. 4. Fig. 8 is a sectional view of a folded strip of paper such as the attachment is adapted to receive 80 and to cut along the folds. Fig. 9 is a view corresponding to Fig. 8 showing the position of the cutting knives with reference to the strip of paper. Fig. 10 is a detail perspective view showing the paper guide and 85 cutter at one side of the attachment.

The typewriter machine is designated by the reference character 12, the frame being shown in broken lines in Fig. 1. The carriage 13 is mounted on the frame in the 90 usual manner and comprises a transverse rod or bar 14 and a curved guide plate 15 over which the paper is fed between the platen 16 and a coöperating feed roll 17. All of these parts are well known, are arranged differently in machines of different makes and form no part of my present invention.

The attachment with which my invention is particularly concerned comprises a frame 100 having a pair of similar side strips 21, two sets of transverse strips 22 and 23, each constituting a guide between which the paper is fed as hereinafter explained, and a transverse strip 23a. Riveted or otherwise 105 suitably secured to the side strips 21 are brackets 24 which are adapted to be removably secured by thumb screws 25 or other suitable means to the cross-bar 14 of the typewriting machine. The set of strips 23 is located near the outer end of the attachment while the set 22 is located near its inner

end and over the guide plate 15 of the carriage.

Near the strips 23 and secured to the side strips 21 are a plurality of cutters 26 which 5 are adapted to extend inwardly between the layers of a strip of folded paper, as clearly indicated in Fig. 9, and to cut the paper at the longitudinal folds as shown in Fig. 10. Each of the knives has an end projection 27 10 which tends to slightly separate between the sheets of the paper in advance of the knife which is indicated at 28. Near the opposite end of the frame from the cutting knives are a pair of ribbon supports 29 which are 15 curved at 30 to conform to the surface of the platen 16 of the machine. At their inner ends they are pivotally and removably mounted on the side strips 21 by means of bolts 31 and thumb nuts 32, or by some other 20 suitable means which permits the removal of the ribbon supports as well as the clamping of them in position, as shown in full lines in Fig. 4 and in Fig. 6. Each of the supports 29 has a notch 33 which is adapted to receive 25 a loop 34 of typewriter ribbon as shown in Figs. 3 and 4. The ribbon loop may readily be mounted in position on the supports 29 by swinging one of them about the bolt 31 as a pivot into the position 30 shown in dotted lines in Fig. 4, and then swinging it back to the position shown in full lines with the ribbon in place.

In order to prevent the slipping of the supports 29, due to the tension in the ribbon, 35 I prefer to utilize projections 35 from the inner corners of the frame, to coöperate with holes 36 in the supports. By this means each of the supports is fixed at two points and consequently will not swing on its pivot 40 31 if it is clamped in place by the thumb nut 32.

The number of cutters 26 and the number 45 of ribbon loops mounted on the supports 29 will depend upon the number of folds in the paper strip which is to be used in the machine,—for example, if the paper strip is folded twice, making three layers as shown in Figs. 8 and 9, only two cutters 26, one on each side, and only a single loop of ribbon 50 are required. If, however, the paper were folded, say, three times, making five layers, four cutters, as shown in Fig. 4, become desirable and two superposed ribbon loops will be mounted on the supports.

55 The method of utilizing the machine will be readily understood from the foregoing description of the apparatus, but will now be briefly outlined as follows:—Assuming that a strip 40 of paper having two longitudinal folds, making three lays, *a*, *b*, and *c*, is to be used in the machine, one ribbon loop such as 34 is mounted on the supports 29 and stretched into position as already described. The strip 40 is then fed between 60 the guide strips 23 as shown in Fig. 1. The

edges are first cut back sufficiently to permit the end of the strip to be introduced into the machine so that the feed mechanism will actively engage the end of the strip. A pair of the cutters 26 are then arranged 70 with reference to the layers *a*, *b*, and *c*, as shown in Fig. 9. The strip is then led over the transverse strip 23, over the usual guide 75 15, and between the feed roll 17 and the platen. The strip is wrapped around the platen with the layer *c* under the ribbon loop 34 as clearly shown in Fig. 1. The strip *b* is led through the loop 34 and the strip *a* is led over the loop and under the usual typewriter ribbon which is indicated by the reference 80 character 41. The strip is then led between the transverse guide strips 22. When the strip is in position the typewriter machine may be operated in the usual manner, the type striking on top of the ribbon 41, and 85 making an impression on each of the strips *a*, *b* and *c*, by reason of the respective ribbon strips which are over them. The typewritten matter is visible as soon as the platen is fed forward to bring it out from 90 under the ribbon in the usual way. Once the strip is led through as above described, it will be fed forward automatically by the typewriter feed and the cutters 26 will become active in slitting the folded strip into 95 the independent strips *a*, *b*, and *c*. The folded strip 40 may be provided in indefinite lengths from a supply roll or package 100 (not shown), conveniently located near the outer end of the attachment. If the strips have a large number of spaced forms printed on them to constitute bills, for example, each bill as completed may be readily removed from the machine by cutting off the strips in any suitable way. Preferably, the edge 105 of the upper guide strip 22 is sharpened as indicated in Figs. 1 and 2, to enable the strips to be neatly torn against the cutting edge thus formed.

110 While I have shown and described my improved attachment in connection with an “Oliver” typewriting machine, to which it is particularly well adapted, my invention is not limited in this regard and may be readily applied to various well known types 115 of machines.

Variations in the structure of the attachment may be effected within the spirit and scope of my invention, and I intend that only such limitations be imposed as are indicated in the appended claims.

115 What I claim is:

1. An attachment adapted to be removably secured to the carriage of a typewriting machine, comprising a frame, means for 125 guiding a longitudinally folded strip of fabric, and cutters for severing the strip at the folds.

2. An attachment adapted to be removably secured to the carriage of a typewrit- 130

- ing machine, comprising a frame, means for guiding a longitudinally folded strip of fabric, and cutters adjacent to the guide means for severing the strip at the folds.

3. An attachment adapted to be removably secured to the carriage of a typewriting machine, comprising a frame having pairs of transverse strips constituting guides for a longitudinally folded strip of fabric, and cutters extending inwardly from opposite sides of the frame for severing the strip at the folds.

4. An attachment, for typewriting machines, comprising means for guiding a longitudinally folded strip to the platen of the machine, cutters for dividing the strip along the lines of the fold, and means for supporting superposed strips of printing ribbon in position to produce manifold copies on the several copy strips.

5. An attachment adapted to be removably secured to the carriage of a typewriting machine, comprising a frame, means for guiding a longitudinally folded strip of fabric, side cutters for severing the strip at the folds, and a transverse cutting member.

6. An attachment adapted to be removably secured to the carriage of a typewriting machine, comprising a frame having pairs of transverse strips constituting guides for a longitudinally folded strip of fabric, cutters extending inwardly from opposite sides of the frame for severing the strip at the folds, and another pair of transverse strips, one of which is provided with a cutting edge.

7. An attachment, for typewriting machines, comprising means for guiding a longitudinally folded strip to the platen of the machine, side cutters for dividing the strip along the lines of the fold, means for supporting superposed strips of printing ribbon in position to produce manifold copies on the several copy strips, and another pair of transverse strips, one of which is provided with a cutting edge.

8. An attachment adapted to be removably secured to the carriage of a typewriting machine, comprising a frame having pairs of transverse strips constituting guides for a longitudinally folded strip of fabric, cutters extending inwardly from opposite sides of the frame for severing the strip at the folds, and means for supporting superposed strips of printing ribbon in position to produce manifold copies on the strips.

9. An attachment adapted to be removably secured to the carriage of a typewriting machine, comprising a frame having pairs of transverse strips constituting guides for a longitudinally folded strip of fabric, cutters extending inwardly from opposite sides of the frame for severing the strip at the folds, means for supporting superposed strips of printing ribbon in position to pro-

duce manifold copies of the strips, and another pair of transverse strips, one of which is provided with a cutting edge.

10. An attachment adapted to be removably secured to the carriage of a typewriting machine, comprising a frame having pairs of transverse strips constituting guides for a longitudinally folded strip of fabric, cutters extending inwardly from opposite sides of the frame for severing the strip at the folds, and supports removably secured to the frame for stretching a loop of printing ribbon in position to produce manifold copies on the strip.

11. An attachment for typewriting machines having a carriage, a platen thereon, and a feed mechanism; comprising a frame adapted to be removably secured to the carriage, guide strips thereon near its respective ends, and cutters extending inwardly from opposite sides of the frame.

12. An attachment for typewriting machines having a carriage, a platen thereon, and a feed mechanism; comprising a frame adapted to be removably secured to the carriage, guide strips thereon near its respective ends, cutters extending inwardly from opposite sides of the frame, and another pair of transverse strips, one of which is provided with a cutting edge.

13. An attachment for typewriting machines having a carriage, a platen thereon, and a feed mechanism; comprising a frame adapted to be removably secured to the carriage, guide strips thereon near its respective ends, cutters extending inwardly from opposite sides of the frame, and auxiliary ribbon supports pivotally attached to the frame.

14. An attachment for typewriting machines having a carriage, a platen thereon, and a feed mechanism; comprising a rectangular frame adapted to be removably secured to the carriage, transverse guide strips thereon in pairs near the respective ends of the frame, cutters extending inwardly from the opposite side of the frame, and auxiliary ribbon supports pivotally and removably attached to the frame and adapted to extend over the platen near its end, said frame having projections to fix the position of the ribbon supports.

15. An attachment for typewriting machines having a carriage, a platen and a printing ribbon; comprising a frame adapted to be removably secured to the carriage and having transverse guide strips to receive a longitudinally folded strip of paper, cutters extending inwardly from the sides of the frame for cutting the strip longitudinally along the lines of the folds, and ribbon supports secured to the frame and adapted to stretch a plurality of superposed printing ribbon strips between the platen and the ribbon of the typewriting machine,

whereby the strips after being cut may be fed in position to receive an impression either from the typewriter ribbon or from the copy ribbon.

5 16. An attachment for typewriting machines having a carriage, a platen and a printing ribbon; comprising a frame adapted to be removably secured to the carriage and having transverse guide strips to receive 10 a longitudinally folded strip of paper, cutters extending inwardly from the sides of the frame for cutting the strip longitudinally along the lines of the folds, and ribbon

supports secured to the frame and adapted to stretch a plurality of superposed printing ribbon strips between the platen and the ribbon of the typewriting machine, whereby the strips after being cut may be fed in position to receive an impression either from the typewriter ribbon or from the copy ribbon; and another pair of transverse strips, one of which is provided with a cutting edge. 15 20

In witness whereof, I have hereunto set my hand this 14th day of May, 1915.

RICHARD D. ANANSON.
